ADJUSTABLE SUPPORT MEANS

James J. Jacobson, New York, N.Y., assignor to Harrison Home Products Corp., New York, N.Y.

Filed Mar. 3, 1960, Ser. No. 12,563

5 Claims. (Cl. 223—120)

The present invention relates to a novel support stand.

More specifically, the present invention relates to a support stand which is especially suitable for use in conjunction with a dress form, for supporting the latter while it is being used.

According to the present invention, there is provided a support stand which is adjustable in height in a simple, efficient and extremely economic manner.

It is therefore an object of the invention to provide a generally improved support stand.

Another object of the invention is the provision of a support stand which is easily collapsible and adjustable to a plurality of predetermined heights.

A further object of the present invention is the provision of a support stand which is easily collapsible and adjustable to a plurality of predetermined heights, said stand being made in a novel, simplified and economic manner.

The above and other objects, features and advantages of the present invention will be more fully understood from the following description considered in connection with the accompanying illustrative drawings.

In the drawings:

FIG. 1 shows a front elevational view of the support stand in accordance with the invention, further showing a dress form supported thereon;

FIG. 2 shows the area identified by "a" in FIG. 1, partly in section and on a larger scale;

FIG. 3 is a side view taken in the direction of the arrow 3 in FIG. 2; and

FIGS. 4a, b and c show three different conditions of the stand for obtaining three different heights therefor.

Referring now to the drawings, there is shown a dress form 10 supported by the support stand 12 in accordance with the invention. The support stand 12 comprises a base 14 which may be a tripod as shown consisting of removable legs 16, 18 and 20, or said base may comprise any other suitable means adapted to rest on a floor. A rod-like first member 22 extends upwardly from junction 24 of the tripod legs, said member 22 terminating at its upper end in an open ended tubular part 26. Support stand 12 is provided with a second member 28 comprising an upper vertically extending rod-like member 30 provided at its upper end with a transverse member 32. Member 30 is adapted to be inserted, at its lower end, into tubular part 26, and for that purpose, the outside diameter of member 30 is a fraction smaller than the inside diameter of tubular part 26. In this way, member 30 is easily insertable into tubular part 26 and is also rotatably mounted therein. Dress form 10 rests upon the transverse member 32, which defines a supporting surface for said dress form, and particularly upon the opposite ends 34 and 36 thereof. These latter ends 34 and 36 may be provided, as shown, with anti-friction rubber boots so as to prevent lateral relative motion between the dress form 10 and the rod 32. An inverted V-shaped member 38 may also be provided, extending upwardly of rod 32, and adapted to be in registry with the opening 40 at the upper end of the dress form. Member 38 is used to guide dress form 10 onto support stand 12 and is reachable through opening 40 in the dress form in order to permit the latter to be rotated.

It will be noted that the depth *d* of the tubular part 26 (as shown in FIG. 2) limits the longitudinal extent to

2

which rod-like member 30 penetrates into rod-like member 22, and accordingly, controls the vertical position or level of transverse member 32 to in turn control the height at which the dress form will be disposed.

5 An asymmetrical inverted U-shaped member 42 is secured to rod 30, above the lower end of the latter, as by welding 44. U-shaped member 42 has a pair of depending legs 46 and 48, respectively, unequal in size, leg 46 being shorter than leg 48 and leg 48 terminating above the lower end 31 of rod 30. The cross section of legs 46 and 48 is the same size as that of rod 30, and accordingly, each of legs 46 and 48 is insertable in tubular part 26.

When it is desired to change the height level of the 15 dress form from the condition shown in FIG. 1, all that is necessary to do is to remove rod 30 from tubular part 26 and insert in the latter, instead, leg 48 or leg 46, as shown in FIGS. 4b and 4c, respectively. It will of course be understood that due to the relative vertical disposition 20 of the lower ends of legs 46, 48 and rod 30, the resulting level of transverse rod 32 will be changed depending on whether it is rod 30, leg 48 or leg 46 which is inserted into the tubular part 26. Accordingly, in the particular embodiment shown, it will be apparent that the level of 25 transverse rod 32, and thus dress form 10 will be highest when rod 30 is inserted into tubular part 26, lowest when leg 46 is inserted therein, and intermediate the highest and lowest when leg 48 is inserted therein. As best seen in FIG. 2, the spacing between legs 46 and 48 and rod 30 is sufficient to provide clearance for the wall of tubular part 26 when either leg 46 or leg 48 is inserted into said tubular part, as best seen in FIGS. 4b and 4c.

It is thus seen that the support stand aforesaid is extremely simple in construction and permits easy adjustability thereof to a plurality of vertical heights. It 35 will also be noted that due to the fact that rod 30, as well as legs 46 and 48, are rotatably mounted in tubular part 26, any dress form 10 supported on the stand can easily be rotated, as desired.

It will be understood that while one U-shaped member 42 has been shown, one or more such U-shaped members could be provided and secured to rod 30 to increase the 40 range of adjustability of support stand 12. It will also be understood that member 30, and legs 46 and 48, could be provided with tubular end parts and part 26 could 45 then be solid. Also, it will be understood that the U-shaped member 42 could be secured to member 22 instead of to member 30, and still provide the same range of adjustability in support stand 12.

While I have shown and described the preferred embodiments of my invention, it will be understood that the invention may be embodied otherwise than as herein specifically illustrated or described, and that in the illustrated embodiment certain changes in the details of construction and in the form and arrangement of parts may 50 be made without departing from the underlying idea or principles of this invention within the scope of the appended claims.

Having thus described my invention, what I claim and 55 desire to secure by Letters Patent is:

1. Support means comprising, a base adapted to rest on a floor, a first member supported by said base and extending upwardly therefrom, a second member provided at the upper end thereof with a supporting surface in fixed 60 relation therewith, and cooperating means on said first member adjacent the upper end thereof and on said second member adjacent the lower end thereof for releasably and rotatably supporting said second member on said first member in a vertical disposition of said second member and in a selected one of a plurality of relative 65 vertical dispositions corresponding to a selected one of a plurality of heights for said supporting surface, said co-

operating means comprising a tubular part at the upper end of said first member and a plurality of downwardly extending parts of unequal lengths adjacent the lower end of said second member and in fixed relation therewith, each of said downwardly extending parts being insertable into said tubular part a predetermined fixed amount.

2. Support means comprising, a base adapted to rest on a floor, a first member supported by said base and extending upwardly therefrom, a second member provided at the upper end thereof with a supporting surface in fixed relation therewith, and cooperating means on said first member adjacent the upper end thereof and on said second member adjacent the lower end thereof for releasably and rotatably supporting said second member on said first member in a vertical disposition of said second member and in a selected one of a plurality of relative vertical dispositions corresponding to a selected one of a plurality of heights for said supporting surface, said cooperating means comprising a tubular part at the upper end of said first member and an inverted U-shaped member fixedly secured to said second member adjacent the lower end thereof, said U-shaped member having a pair of depending legs of length unequal to each other, and each of said legs as well as the lower end of said second member being insertable into said tubular part a predetermined fixed amount.

3. Support means for a dress form comprising, a base adapted to rest on a floor, a first member supported by said base and extending upwardly therefrom, a second member provided at the upper end thereof with a supporting surface for said dress form in fixed relation therewith, and cooperating means on said first member adjacent the upper end thereof and on said second member adjacent the lower end thereof for releasably and rotatably supporting said second member on said first member in a vertical disposition of said second member and in a selected one of a plurality of relative vertical dispositions corresponding to a selected one of a plurality of heights for said dress form supporting surface, said cooperating means comprising a tubular part at the upper end of said first member and an inverted U-shaped member fixedly secured to said second member adjacent the lower end thereof, said U-shaped member having a pair of depending legs of length unequal to each other, and each of said legs as well as the lower end of said second member being insertable into said tubular part a predetermined fixed amount.

4. Support means for a dress form comprising, a base adapted to rest on a floor, a first member supported by said base and extending upwardly therefrom, a second member provided at the upper end thereof with a supporting surface for said dress form in fixed relation ther-

with, and cooperating means on said first member adjacent the upper end thereof and on said second member adjacent the lower end thereof for releasably and rotatably supporting said second member on said first member in a vertical disposition of said second member and in a selected one of a plurality of relative vertical dispositions corresponding to a selected one of a plurality of heights for said dress form supporting surface, said cooperating means comprising a tubular part at the upper end of said first member and an inverted U-shaped member fixedly secured to said second member adjacent the lower end thereof, said U-shaped member having a pair of depending legs of length unequal to each other, and each of said legs as well as the lower end of said second member being insertable into said tubular part a predetermined fixed amount, said supporting surface comprising anti-friction means for preventing relative movement between said dress form and said surface.

5. Support means for a dress form comprising, a base adapted to rest on a floor, a first member supported by said base and extending upwardly therefrom, a second member provided at the upper end thereof with a supporting surface for said dress form in fixed relation therewith, and cooperating means on said first member adjacent the upper end thereof and on said second member adjacent the lower end thereof for releasably and rotatably supporting said second member on said first member in a vertical disposition of said second member and in a selected one of a plurality of relative vertical dispositions corresponding to a selected one of a plurality of heights for said dress form supporting surface, said cooperating means comprising a tubular part at the upper end of said first member and an inverted U-shaped member fixedly secured to said second member adjacent the lower end thereof, said U-shaped member having a pair of depending legs of length unequal to each other, and each of said legs as well as the lower end of said second member being insertable into said tubular part a predetermined fixed amount, said supporting surface comprising anti-friction means for preventing relative movement between said dress form and said surface, and an inverted V-shaped member extending upwardly of said supporting surface for guiding said dress form onto the support means.
